UNITED STATES PATENT OFFICE.

IRA A. WEAVER, OF SPRINGFIELD, ILLINOIS, ASSIGNOR TO THE WEAVER MANUFACTURING COMPANY, OF SPRINGFIELD, ILLINOIS, A CORPORATION OF ILLINOIS.

TORPEDO.

1,290,815.

Specification of Letters Patent.

Patented Jan. 7, 1919.

Application filed April 13, 1918. Serial No. 228,293.

To all whom it may concern:

Be it known that I, IRA A. WEAVER, a citizen of the United States, residing at Springfield, in the county of Sangamon and State of Illinois, have invented certain new and useful Improvements in Torpedoes, of which the following is a specification.

My invention aims at improvements in torpedoes of the type adapted and capable of distributing or dropping bombs or other explosives while in transit, such, for example, as those suitable for the destruction of submerged submarines. One object of the invention is the provision of an apparatus of this kind whereby the bombs or other explosive appliances will be automatically discharged at predetermined intervals in such a way as to have practically no detrimental effects on the course of the traveling torpedo. Another feature of the invention is the provision of adjustable means for governing or regulating the period during which the torpedo shall distribute or discharge its bombs, and a further salient purpose of the invention is to provide suitable locking means for the mechanism controlling the discharge of the bombs, whereby danger of accidents is eliminated. Additionally, the appliance is so constructed that all of the bombs or explosive shells of the magazine shall be exploded together or conjointly upon the torpedo making a direct hit. The production of a device of this general character which is without complications, which is inexpensive to produce, which is effective in results, which is locked against unintentional or premature explosion, and which may be readily and easily combined with a torpedo of general standard dimensions and design, is, of course, one of the main and leading objects of the invention. Facility of removal of the bomb magazine and its associated timing mechanisms and their ready replacement in position in the torpedo constitutes a further valuable characteristic of the invention.

In order that those skilled in this art may have a full and complete understanding of the invention and its various advantages, both from a structural and functional standpoint, I have illustrated in the accompanying drawings forming a part of this specification, a preferred embodiment of the invention, and throughout the various views

of these drawings like reference characters 55 refer to the same parts.

In the drawings:

Figure 1 shows the torpedo in the launching-tube, the latter being partially broken away to more clearly indicate the construction;

Fig. 2 illustrates the torpedo in elevation with its shell or casing cut away at certain points;

Fig. 3 is an enlarged, longitudinal, sectional view of the front portion of the torpedo;

Fig. 4 is a cross-section through the bomb-magazine;

Fig. 5 is a front-end elevation of the launching-tube and torpedo;

Fig. 6 is a rear end elevation of the same parts;

Fig. 7 is a detail of the controlling means governing the discharge of the bombs, and

Fig. 8 shows on a small scale the manner in which the torpedo delivers or discharges its bombs from below.

The torpedo characterized 20 as a whole, in a general way, is in most respects like or similar to the standard appliance having the usual shell or casing 21 housing a compressed-air storage compartment 22, a turbine 23 with suitable controlling-means, and a propeller-shaft 24 driven by the turbine 85 and equipped at its rear end with a pair of screw propellers 25 and 26.

At its forward end the torpedo, just in advance of the compressed-air reservoir, has a bomb-magazine chamber 27, and at its head 90 or nose the torpedo has another compartment 28 adapted to contain the timing-gearing. These two chambers 27 and 28 have between them a partition-wall 29 provided centrally with a bearing 30 for the journal 95 31 of a rotary bomb-magazine or revolvable-cradle 32 having at its rear end a cylindrical part 33 supported by and capable of turning on a bearing-member 34 secured to and extended forwardly from the front face of the 100 dished or bellied wall 35 of the air reservoir 22. In the present instance, as is clearly illustrated, this cradle or magazine member is constructed to accommodate five bombs 36, 37, 38, 39, and 40, but it will be readily 105 understood that the number of bombs is immaterial.

The compartment 27 at its lower portion

is provided with an opening 41 of substantial size through which the bombs are individually discharged or delivered at intervals, such opening being ordinarily closed by the 5 door or cover 42 having at its rear end a hook-shaped member 43 secured to its inner or upper face and adapted to hold the cover in closed position by extending through a hole 44 in an adjacent stationary inclined 10 wall 45 forming a direct extension of the similarly-disposed rear wall 46 of each bomb compartment, as such compartment, during the rotation of the magazine or cradle, is brought to its lowermost position. At its 15 front end the door or cover has a bracket 47 to which a catch 48 is pivoted, the tail of such catch or lock being adapted to be engaged by the first bomb as it turns into discharging position, whereby the cover is 20 automatically unlocked or released and falls away from the opening. It will be perceived that the front end of such door or cover is first released and as this drops somewhat under its own weight, it catches 25 the water above it which quickly swings the cover down, causing the complete release or freeing of its rear end so that the cover as a whole drops away from the torpedo.

A pipe or tube 50 extends centrally 30 through the air-reservoir and through its end walls and accommodates within it a shaft 51 extended through the turbine and into the propeller-shaft 24 with which it is operatively connected, whereby the rotation 35 of the propeller-shaft effects the revolution of this forwardly-extended shaft, the front end of which is fitted and keyed in a sleeve 52 which it drives. This sleeve in turn is keyed to a nut 53 threaded into the part 31, 40 the internal threads of the latter extending only part way of the length, whereby turning of the shaft 51, sleeve 52, and nut 53, brings about the longitudinal bodily travel of the latter until its threads are free from 45 those of the part 31. A collar 54 surrounds and is longitudinally-slidable on the cylindrical exterior of the hub 31 and is so shaped and fixed over the front end of the bombs in their magazine compartments as to prevent 50 their unintentional lengthwise displacement except when permitted to do so by the nut having traveled forwardly. In other words, the position of the nut determines whether or not the bombs are axially 55 slideable in the magazine. Such control is secured by providing an inwardly-extended lug 55 on the collar overlying the face of the nut and slidably accommodated in a lengthwise slot 56 in hub 31. This part of the device 60 is provided as a safety appliance to prevent unintentional or premature detonation of the bomb before the torpedo has traveled at least a short distance. In other words, it 65 renders the torpedo safe for handling before discharge from its launching-tube.

Sleeve 52 is equipped with a pinion 57 which, by suitable speed reduction gearing contained in a gear-casing 58 and not necessary to be described in detail because it may be of any usual or suitable character, drives 70 a pinion 59 and a shaft 60. Such shaft has loosely mounted thereon a pinion 61, in mesh with a gear 62 on the revoluble bomb-magazine hub 31 and an associated clutch-element 63. Slidable on the shaft is a companion clutch-element 64 pressed, as by a spring 65, toward element 63. When the clutch is permitted to be operative, the multi-chambered bomb receptacle or storage device is rotated at a comparatively slow speed by 80 the turbine which drives the propeller-shaft.

The timing-mechanism includes also a shaft 70, revoluble and longitudinally slideable in the bearing 71 in the front-wall of 85 the gear-housing, which has a gear 72 fixed thereto so as to be rotated therewith, the gear having on its inner or rear face a circular flange or cam element thickened at 74, at which point it is cut through at 75, the 90 gap or recess having an inclined rear surface 76 (see Fig. 7). As is clearly illustrated, this gap or recess is not of the full width of the flange (see Fig. 3), being approximately one-half or two-thirds of such 95 width. Shaft 70 has a collar 77 pinned thereto against which and against the front face of the gear-casing, a coil expansion-spring 78 encircling the bearing 71 presses, tending to force the shaft forwardly and to 100 carry the gear 72 into mesh with its companion pinion 59.

The front end of the shaft projects through a hole in the nose-piece 79, the end of the shaft having a cross-pin 80 by which 105 the shaft may be turned. When the shaft is pushed inwardly, as indicated in Fig. 3, the terminal portion of the shaft is received in a cavity or recess 81 in such nose-piece.

The timing or regulating appliance includes also a lever 82 fulcrumed at 83 and having a lug or finger 84 adapted to ride on the outer curved surface of flange or cam 73 and passed through the gap 75 when the latter, during the rotation of gear 72 and the 115 cam, comes into register therewith.

Lever 82 has another arm 85 adapted to engage a flange or circular shoulder on the movable clutch-element 64 and holds said element against the action of spring 65 in 120 inoperative relation to the companion clutch-element 63. A lateral finger 86 on lever-arm 85 is provided to engage between the teeth of pinion 61 and lock it and the bomb-magazine against turning. It will be seen, therefore, that this single lever locks the clutch open and also locks the magazine from turning. When the gap in the cam comes into register with the finger 84, however, the latter will be positively depressed by the in- 125 130

- clined face 76 and the two locking means positively moved into unlocking position, whereupon the clutch will become active and the bomb-magazine will begin to rotate.
- 5 The gearing is so arranged that gear 72 will make one complete revolution during the entire travel of the torpedo. By pushing rearwardly shaft 70 and then turning it any predetermined amount, the gap 75 may be 10 moved a distance away from the finger 84 a definite amount corresponding to the required time interval, so that until the gear has turned this amount, that is, until the torpedo has traveled a certain distance, the 15 bomb magazine is locked against rotation.
- As indicated above, however, when the gap 75, during the turning of gear 72, comes into register with the finger 84, the latter passes down through it by reason of the 20 positive depressing action of the inclined surface 76, thereby rocking the lever as a whole, freeing the clutch which immediately becomes operative to drive the pinion, and also unlocks the pinion, whereupon the turning 25 of the magazine begins.
- In order to set or adjust this timing mechanism before the torpedo leaves its launching-tube, thereby determining beforehand when the discharge of the bombs 30 or shells shall begin, I provide on the exterior of such launching-tube a plurality of aligned bearings 90, 91, 92, and 93 (Fig. 1), supporting an oscillatory slideable hollow shaft or sleeve 94, to the front end of which 35 a radial-arm 95 is fixed, such arm being of a proper length so that its outer or free end may, by the turning of the hollow shaft or sleeve, be swung into and out of register with shaft 70. To permit such oscillation 40 and lengthwise movement of the shaft and arm, the rear end of the former is equipped with a suitable manipulating handle 96.
- This hollow-shaft has within it another shaft 97 whose front part projects beyond 45 the corresponding end of such incasing hollow-shaft and the protruding end of the inner shaft is fitted with a sprocket-wheel 98 co-acting with the sprocket-chain 99, which in turn co-operates with a sprocket-wheel 100 50 mounted on the outer end of arm 95. These wheels and the companion chain, as well as the supporting-arm may, if desired, be appropriately incased as may be convenient. The inner face of the sprocket-wheel 100 or 55 the shaft on which it is fitted is shaped to fit over the front end of shaft 70 and recessed to receive the cross-pin 80. As has been indicated, these interfitted shafts and their appurtenant parts, are not only rotatable 60 in the bearings, but also to a slight extent longitudinally slideable therein, whereby the arm 95 may be swung into operative position and then shifted slightly rearwardly, thereby operatively coupling gear 100 and 65 shaft 70, and pushing the latter back against
- the action of spring 78, and shifting gear 72 rearwardly out of mesh with its companion pinion 59. When thus freed, this gear 72 and its associated cam flange 73, may be turned by rotating shaft 97 so as to set the 70 timing of the delivery of the bombs, such discharge, as will be readily understood, being determined by the distance the gap 75 is moved away from the finger 84. To permit such manipulation of the parts, the rear end 75 of shaft 97 is fitted with a handle 101 and an adjacent graduated scale or index 102 indicating the time period for which the 80 torpedo is set before the discharge of the bombs will begin.
- Each bomb or shell has a spring-pressed firing-pin 105 protected by being well within the end of such explosive appliance, the latter being thus rendered relatively safe to handle. This pin has a small breakable 85 chain 106 fastened thereto, the other end of the chain being secured to the bomb magazine at 107. When the first bomb, during the rotation of the magazine or storage cradle reaches or approaches its lowermost position, it releases catch 48 and pushes down the front end of cover 42. The water catching the latter, rocks it down until its rear end is released, whereupon it falls away from the torpedo, leaving the opening or 90 exit 41 free. During the discharge or descent of the bomb through this opening, its back curved end slides down the incline 45, 46, and the bomb passes through the exit 95 opening in the direction indicated in dotted lines in Fig. 3. Thereupon the strain put upon the chain causes the retraction of the firing-pin, and upon the severance of the chain, the freed pin, under the influence of its spring, detonates the bomb or shell, the 100 timing of the explosions being such that the bomb will drop to some depth before bursting. In the meantime, of course, the torpedo has passed out of harm's way.
- To assist in exploding all of the bombs at 110 the same time when the traveling torpedo strikes an object, the revoluble bomb-carrier has a disk 110 fitted on and rotatable with the magazine-hub 31, such disk having lugs or projections 111 in line with or directly 115 in front of the firing-pins. When, therefore, the safety-collar 54, having been automatically freed during the first section of the travel of the torpedo, all of the bombs suddenly slide forwardly, if the torpedo makes 120 a direct hit, the chains pull on all of the firing-pins, and then break, and such pins strike the lugs and simultaneously detonate all the bombs.
- As to the accessibility and removability 125 of the timing-gearing and the bomb-magazine, it should be observed that the casing of chamber 28 is readily detachable owing to its telescopic fit over the outer part of the partition-wall 29. Such removal renders 130

the timing appliance easily reached and de-mountable if desired by removing the screws holding the casing to the partition-wall. The shell or wall of compartment 27, which may conveniently be integral with the wall 29 is also easily removed from the main body of the torpedo because of its telescopic fit therewith. Such removal permits the de-mounting of the bomb-magazine with facility and despatch. The shaft being sectional as specified, permits such ready removal of the parts without difficulty.

This improved and novel appliance is operated practically as follows, assuming that the magazine has been charged with bombs with their chains properly secured, and that the safety-collar 54 has been rendered operative to hold the bombs against movement by screwing in nut 53. A submarine, which it is desired to destroy, having been sighted at a range or distance away of two thousand yards, for example, the gunner or operator, by manipulating the handles 96 and 101 and by reading the dial 102, shifts gear 72 rearwardly out of mesh with its operating-pinion 59, and then turns such gear and its cam-flange an amount corresponding to such distance. During this operation, there is no danger of finger 84 passing through the gap in the cam-flange, because if such gap should by chance come into register with the finger, the latter, owing to the retracted position of the cam-flange, is riding on the part 74. Stated otherwise, the finger can only pass through the gap when the gear and its flange are in their advanced position with the gear in mesh with its pinion. Arm 95 and its associated parts are then swung out of the way and gear 72, under the influence of its spring 78, slides forwardly into cooperative driving relation with its pinion. The torpedo is then launched in the usual way. After having traveled a short distance, the nut 53 will have been fed forwardly by the turning of shaft 51, sufficiently to release it from the internal threads of hub 31. This, of course, enables the safety collar 54 to slide forwardly on the hub if the torpedo strikes an object and the impact shifts the bombs forwardly. If this occurs, all of the bombs will be exploded at the same time in the manner described. Conceding that no such hit occurs, the torpedo travels along for 1,750 yards, whereupon, the first bomb is discharged from the torpedo followed by the others at equal timed intervals. This spacing of the bombs is so predetermined and calculated that one of them, assuming that the range and direction of travel were correct, is practically certain to entirely destroy or seriously cripple the submerged submarine. Before such first bomb is delivered, the constant slow rotation of flange 73 brings its gap or passage 75 beneath finger

84, whereupon the clutch element 64 and the pinion 61 are immediately and positively unlocked or released and the turning of the bomb-magazine begins and continues indefinitely, being revolved, as well as the time-gearing, by the motive power which drives the torpedo propeller-shaft. The bringing of the first bomb into place releases cover 42 which, of course, in falling away from the torpedo, is lost. Then the bombs are dropped in succession as described. The spent torpedo floats on the surface of the water and may be recovered, refilled with bombs, and used repeatedly.

It will be appreciated, therefore, that the various objects and purposes sought to be accomplished by the production of a device of this kind have been consummated and completed in the improved torpedo herein illustrated and described. It is to be understood, however, that the invention is not limited and restricted to the precise and exact features of structure presented, because many minor mechanical changes may be made in the torpedo without departure from the substance of the invention and without the sacrifice of any of its substantial benefits and advantages.

I claim:

1. An appliance of the character described comprising in combination, a torpedo, a bomb-magazine in said torpedo, means to discharge said bombs from the torpedo in succession, a timing-mechanism detachably secured in said torpedo, and a casing constituting a transverse section of the torpedo shell covering said timing-mechanism and removably associated with and forming an extension of the main body of the shell of the torpedo, substantially as described.

2. An appliance of the character described comprising in combination, a torpedo, a bomb-magazine in said torpedo, means to discharge said bombs from the torpedo in succession, a timing-mechanism detachably secured in said torpedo, and a casing forming the front tapered part of the torpedo-shell covering said timing-means and removably associated with said shell, substantially as described.

3. An appliance of the character described comprising in combination, a torpedo, a bomb-magazine detachably secured in said torpedo, means to discharge the bombs in succession from said torpedo, means governing the time of said bomb discharge, and a casing constituting a transverse section of the torpedo shell inclosing said bomb-magazine associated with and forming an extension of the main body of the shell of the torpedo, substantially as described.

4. An appliance of the character described comprising in combination, a torpedo, a bomb-magazine detachably secured in said

- torpedo, a casing constituting a transverse section of the torpedo shell inclosing said bomb-magazine removably associated with and forming an extension of the main body 5 of the shell of the torpedo, means to discharge the bombs in succession from the torpedo, means governing the time of said bomb discharge, and a casing constituting a transverse section of the torpedo shell inclosing said timing-mechanism and removably associated with and forming an extension of that section of the torpedo shell forming the bomb-magazine casing, substantially as described.
- 10 5. An appliance of the character described comprising in combination, a torpedo having a compressed-air reservoir chamber, a bomb-magazine in said torpedo in front of said compressed-air chamber, means to discharge said bombs from the torpedo in succession, a timing-mechanism in front of said bomb-magazine governing said discharge, and means permitting ready removal of said timing-mechanism from the torpedo, substantially as described.
- 15 6. An appliance of the character described comprising in combination, a torpedo, a revoluble bomb-magazine in said torpedo, and means to revolve said magazine and discharge its bombs from the torpedo in succession, substantially as described.
- 20 7. An appliance of the character described comprising in combination, a torpedo, a revoluble bomb-magazine in said torpedo, and means driven by the motive-power of the 25 torpedo to revolve said magazine and discharge its bombs from the torpedo in succession, substantially as described.
- 25 8. An appliance of the character described comprising in combination, a torpedo, a revoluble bomb-magazine in said torpedo, and means driven by the driving means for the torpedo propeller-shaft to revolve said magazine and discharge its bombs 30 from the torpedo in succession, substantially as described.
- 35 9. An appliance of the character described comprising in combination, a torpedo, a revoluble bomb-magazine in said torpedo, means to revolve said magazine and discharge its bombs from the torpedo in succession, and adjustable timing-means governing said revolution, substantially as described.
- 40 10. An appliance of the character described comprising in combination, a torpedo, a revoluble bomb-magazine in said torpedo, means to revolve said magazine and discharge its bombs from the torpedo in succession, and timing-means controlling the initiation of the revolution of said magazine, substantially as described.
- 45 11. An appliance of the character described comprising in combination, a torpedo, a revoluble bomb-magazine in said
- torpedo, means to revolve said magazine and discharge its bombs from the torpedo in succession, and timing-means driven by the motive power of the torpedo governing the revolution of said magazine, substantially as described.
- 50 12. An appliance of the character described comprising in combination, a torpedo, a revoluble bomb-magazine in said torpedo, means driven by the motive power of the torpedo to revolve said magazine and discharge its bombs from the torpedo in succession, and timing-means driven by the motive-power of the torpedo governing the revolution of said magazine, substantially as described.
- 55 13. An appliance of the character described comprising in combination, a torpedo having an opening for the delivery of bombs therethrough, a bomb-magazine in said torpedo, means to discharge the bombs of said magazine in succession through said opening, a cover for said opening, a plurality of means to secure said cover to the torpedo, and means to release one of said securing means prior to the release of another, substantially as described.
- 60 14. An appliance of the character described comprising in combination, a torpedo having an opening for the delivery of bombs therethrough, a bomb-magazine in said torpedo, means to discharge the bombs of said magazine in succession through said opening, a cover for said opening, means to secure the front and rear ends of said cover to the torpedo-shell, and means to release said front securing means before the release of said rear securing means, substantially as described.
- 65 15. An appliance of the character described comprising in combination, a torpedo having an opening for the delivery of bombs therethrough, a cover for said opening, a hook-shaped retaining means to hold the rear end of the cover in place, other retaining means for the front end of the cover, and means to release said latter retaining means, substantially as described.
- 70 16. An appliance of the character described comprising in combination, a torpedo having an opening for the delivery of bombs therethrough, a movable bomb-magazine in said torpedo, means to move said magazine to cause its bombs to be delivered in succession from the torpedo through said opening, and a sloping wall causing the bomb passing through said opening to be downwardly and rearwardly directed, substantially as described.
- 75 17. An appliance of the character described comprising in combination, a torpedo, a movable bomb-magazine in said torpedo, means to move said magazine to discharge its bombs in succession from the torpedo, means to lock said magazine against

6
movement, and means to unlock said lock, substantially as described.

18. An appliance of the character described comprising in combination, a torpedo, a revoluble bomb-magazine in said torpedo, means to revolve said magazine to discharge its bombs in succession from the torpedo, means to lock said magazine against rotation, and means to unlock said lock, substantially as described.

19. An appliance of the character described comprising in combination, a torpedo, a movable bomb-magazine in said torpedo, means to move said magazine to discharge its bombs in succession from the torpedo, means to lock said magazine against movement, means to unlock said lock, and means to adjust the time of operation of said unlocking-means before the torpedo is launched, substantially as described.

20. An appliance of the character described comprising in combination, a torpedo, a movable bomb-magazine in said torpedo, means to move said magazine to discharge its bombs in succession from the torpedo, means to lock said magazine against movement, and means actuated by the motive-power of the torpedo to unlock said lock, substantially as described.

21. An appliance of the character described comprising in combination, a torpedo, a movable bomb-magazine in said torpedo, means to move said magazine to discharge its bombs in succession from the torpedo, means to lock said magazine against movement, means to lock said magazine-moving-means against operation, and means to unlock said locks, substantially as described.

22. An appliance of the character described comprising in combination, a torpedo, a movable bomb-magazine in said torpedo, means to move said magazine to discharge its bombs in succession from the torpedo, means to lock said magazine against movement, means to lock said magazine-moving-means against operation, and means actuated by the motive-power of the torpedo to unlock said locks, substantially as described.

23. An appliance of the character described comprising in combination, a torpedo, a movable bomb-magazine in said torpedo, means to move said magazine to discharge its bombs in succession from the torpedo, means to lock said magazine against movement, means to lock said magazine-moving-means against operation, and cam-means actuated by the motive power of the torpedo to unlock said locks, substantially as described.

24. An appliance of the character described comprising in combination, a torpedo, a movable bomb-magazine in said torpedo, means to move said magazine to dis-

charge its bombs in succession from the torpedo, means to lock said magazine against movement, means to lock said magazine-moving-means against operation, and cam-means to positively hold said locks in operative position and to render them inoperative, substantially as described.

25. An appliance of the character described comprising in combination, a torpedo, a revoluble bomb-magazine in said torpedo, means to revolve said magazine to discharge its bombs in succession from the torpedo, means to lock said magazine against rotation, means to lock said magazine-revolving means against operation, and cam-means operated by the motive power of the torpedo to positively hold said locks in operative position and to render them inoperative, substantially as described.

26. An appliance of the character described comprising in combination, a torpedo, means in said torpedo adapted to accommodate a bomb, means to hold said bomb in position in the torpedo against substantial movement, and means to shift the position of said holding means after the torpedo has started on its course, thereby permitting bodily movement of the bomb and its explosion in case the torpedo makes a direct hit, substantially as described.

27. An appliance of the character described comprising in combination, a torpedo, means in said torpedo adapted to accommodate a bomb, means to hold said bomb in position in the torpedo against substantial movement, and means driven by the motive power of the torpedo to shift the position of said holding means after the torpedo has started on its course, thereby permitting bodily movement of the bomb and its explosion in case the torpedo makes a direct hit, substantially as described.

28. An appliance of the character described comprising in combination, a torpedo, a magazine in said torpedo adapted to accommodate a plurality of bombs, means common to all of said bombs to hold them in position in the magazine against substantial movement, and means to shift the position of said holding means after the torpedo has started on its course, thereby permitting simultaneous bodily movement of the bombs and their explosion in case the torpedo makes a direct hit, substantially as described.

29. An appliance of the character described comprising in combination, a torpedo, a magazine in said torpedo adapted to accommodate a plurality of bombs, means common to all of said bombs to hold them in position in the magazine against substantial movement, and means driven by the motive power of the torpedo to shift the position of said holding means after the torpedo has started on its course, thereby permitting simultaneous bodily movement of the bombs

and their explosion in case the torpedo makes a direct hit, substantially as described.

30. An appliance of the character described comprising in combination, a torpedo, a revoluble magazine in said torpedo adapted to accommodate a plurality of bombs means to revolve said magazine to discharge the bombs in succession from the torpedo, means common to all of said bombs 10 to hold them in position in the magazine against substantial movement, and means to shift the position of said holding means after the torpedo has started on its course, thereby permitting bodily movement of the 15 bombs and their explosion in case the torpedo makes a direct hit, substantially as described.

31. An appliance of the character described comprising in combination, a torpedo, a revoluble magazine in said torpedo adapted to accommodate a plurality of bombs, means to revolve said magazine to discharge its bombs in succession from the torpedo, means to lock said magazine against 20 rotation, means to unlock said lock after the torpedo has started on its course, means common to all of said bombs to hold them in position in the magazine against substantial movement, and means driven by the motive power of the torpedo to shift the position of 25 said holding means after the torpedo has started on its course, thereby permitting bodily movement of the bombs and their ex-

plosion in the torpedo in case the latter makes a direct hit, substantially as described.

32. An appliance of the character described comprising in combination, a torpedo, a magazine revoluble in said torpedo and adapted to accommodate a plurality of bombs, means driven by the motive power of the torpedo to revolve said magazine to effect the discharge of its bombs in succession from the torpedo, means to lock and unlock said magazine and its rotating means means common to all of said bombs to hold them in position in the magazine against substantial movement therein, and means driven by the motive power of the torpedo to shift the position of said holding means after the torpedo has started on its course thereby permitting bodily movement of the bombs relative to the magazine and their explosion in the torpedo in case the latter makes a direct hit, substantially as described.

33. An appliance of the character described comprising in combination, a torpedo, a bomb in said torpedo, means to deliver the bomb from said torpedo, and a breakable element securing the firing-pin of said bomb to said torpedo whereby the bomb is set off by the movement of the bomb effecting such breakage, substantially as described.

IRA A. WEAVER.
